DESIGN FOR A TEXTILE FABRIC

Seymour Grauer, New York, N. Y.

Application October 26, 1940, Serial No. 96,109

Term of patent 3½ years

To all whom it may concern:

Be it known that I, Seymour Grauer, a citizen of the United States and a resident of the city of New York, in the county of New York and State of New York, have invented a new, original, and ornamental Design for a Textile Fabric, of which the following is a specification, reference being had to the accompanying drawing, forming a part thereof.

The figure is a plan view of a piece of the fabric showing my new design, the unit of which is indicated by dot and dash lines.

I claim:

The ornamental design for a textile fabric, substantially as shown and described.

SEYMOUR GRAUER.
